DESIGN FOR A FLUID DIFFUSER ELEMENT

Curry E. Ford, Lakewood, Ohio, assignor to National Carbon Company, Inc., a corporation of New York

Application February 2, 1940, Serial No. 89,958

Term of patent 14 years

To all whom it may concern:

Be it known that I, Curry E. Ford, a citizen of the United States, residing at Lakewood, in the county of Cuyahoga and State of Ohio, have invented a new, original, and ornamental Design for a Fluid Diffuser Element, of which the following is a specification, reference being had to the accompanying drawing, forming a part thereof.

The drawing is a perspective view of the fluid diffuser element illustrating my new design, a portion of said element being broken away.

I claim:

The ornamental design for a fluid diffuser element, substantially as shown.

CURRY E. FORD.
